[57] CLAIM

The ornamental design for a chair, as shown and described.

DESCRIPTION

FIG. 1 is an elevation view showing the left side of a chair according to our design, the right side being a mirror image thereof;

FIG. 2 is an elevation view showing the front of the chair; FIG. 3 is a top plan view of the chair according to; and, FIG. 4 is an elevation view showing the rear of the chair. The fragmented cross-hatching shown on the seat and backrest in FIGS. 1 through 3 is understood to represent fabric and would be continuous throughout the implied areas. The broken lines shown in all views are for illustrative purposes only and form no part of the claimed design.
